(57) **CLAIM**

The ornamental design for a nuclear reactor boiler divider plate shield, substantially as shown and described.

DESCRIPTION

FIG. 1 is a front perspective view of a nuclear reactor divider plate shield showing the new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a side view thereof; and,

FIG. 8 is a side view thereof.

The claimed design can be used, for example, as radiation shielding.

Applicant reserves the right to modify any of the figures to show, in line drawing format, any feature depicted in solid lines in dashed lines.

Applicant reserves the right to file one or more divisional applications to specifically claim or disclaim certain features depicted in the figures.
